UNITED STATES PATENT OFFICE.

NOBLE H. GILMORE, OF GREENVILLE, MICHIGAN, ASSIGNOR OF THREE-FOURTHS TO JOSEPH M. FULLER, CHARLES S. FULLER, AND WILLIAM H. GILMORE, OF SAME PLACE.

HOISTING APPARATUS.

SPECIFICATION forming part of Letters Patent No. 499,536, dated June 13, 1893.

Application filed November 25, 1892. Serial No. 453,156. (No model.)

To all whom it may concern:

Be it known that I, NOBLE H. GILMORE, of Greenville, in the county of Montcalm and State of Michigan, have invented a new and 5 useful Improvement in Hoisting Apparatus, of which the following is a specification.

My invention pertains to an arrangement of draft-equalizing pulleys below and as an 10 attachment of the upper pulley-block of a compound pulley system, as hereinafter described.

In the accompanying drawings, Figure 1 is a 15 face view of my improved pulley system. Fig 2 is an edge view of the upper pulley-block and the equalizing attachment. Fig. 3 is a cross section on line 3—3 of Fig. 1.

My pulley-block system is composed of three parts, or elements, namely, upper and lower multiple-sheave pulley blocks A and B, 20 which are of a well-known type, the equalizing pulleys C, which are suspended from the upper block A, and a chain D, which runs on the several sheaves of the system, as will be presently described. Each pulley block A 25 and B, has a series of grooved sheaves journaled side by side, on a through pin, and arranged between parallel plates, a, which form part of the frame of the block. The chain D—indicated by dotted lines Fig. 1—passes 30 over the equalizing pulleys C, thence downward and under the respective outer sheaves 1, 1, of the lower block B, next upward over the corresponding outer sheaves 1' 1', of the upper block A, then down and over the second set of sheaves 2, 2, of the lower block B, and next over the corresponding sheaves 2' 2', of the upper block A, and then oversheaves 3, 3 and 3' 3', the end portions c c of said 35 chain passing finally over the central and adjacent sheaves 4, 4, of the lower block B. It will be noted that the sheaves C, are journaled in a frame which is permanently attached to the frame of pulley block A, and that said sheaves are also arranged with their 40 parallel axes in planes at a right angle to the axes of the sheaves of block A. It is apparent that if the system be properly suspended from a suitable support, and tension be ap-

plied to either or both ends of the chain, it will cause the latter to travel through the 50 blocks A, B, and over the sheaves C, and thus raise lower block B. And conversely, if tension be relaxed, the chain D, will travel in the reverse direction, and thus lower the said block B. In practical operation, the sheaves 55 of two such pulley blocks A, B seldom work with exact uniformity, and the same may be said of the chain. This may be due to one or more of several causes; for instance, to unequal friction of the several sheaves, or to 60 twisting of the chain, or the application of the hoisting strain in a direction more or less inclined to the vertical. The provision and arrangement of the sheaves C prevent such result, since they allow the middle portion of 65 the chain to travel freely between the extremities of the lower block B, i. e. between the outer sheaves of such block, so that it readily adjusts itself to the proper relative position, or, in other words, maintains a practically 70 parallel position to the upper block A. Thus the greater friction, draft, and wear, that are incident to the ordinary construction of compound pulley systems of this type, are avoided by a most simple and inexpensive means. 75

What I claim is—

In a compound-pulley system, the combination, with the lower pulley block, B, and the two series of sheaves 1', 2', 3' &c., arranged side by side on the same axis in the upper 30 block, A, of the two "equalizing" pulleys, C and C, arranged on separate but parallel axes at right angles to the first mentioned axis and located directly beneath the outer ones (1' 1') of the said series of upper sheaves, (1', 2', 3' 85 &c.) and the chain, D, arranged as shown, whereby it passes directly from one equalizing pulley (C) to the other, and thence down to the end sheaves of the lower series (1, 2, 3 &c.) as shown and described, for the purpose 90 specified.

NOBLE H. GILMORE.
